(57) **CLAIM**

We claim the ornamental design for a single piece upper control arm, as shown and described.

DESCRIPTION

FIG. 1 is a perspective view of a single piece upper control arm in accordance with the new design.

FIG. 2 is a top view of the single piece upper control arm in accordance with the new design.

FIG. 3 is a bottom view of the single piece upper control arm in accordance with the new design.

FIG. 4 is a first side view of the single piece upper control arm in accordance with the new design.

FIG. 5 is a second side view of the single piece upper control arm in accordance with the new design.

FIG. 6 is a front view of the single piece upper control arm in accordance with the new design; and,

FIG. 7 is a rear view of the single piece upper control arm in accordance with the new design.

In the drawings, the broken lines depict portions of the single piece upper control arm that form no part of the claimed design
